SCRAP CUTTER

John Haller, Northville, Mich.

Application July 5, 1946, Serial No. 681,495

10 Claims. (Cl. 164—10.6)

1

This invention relates to cutting machines, and in particular to sheet material cutting machines.

One object of this invention is to provide a cutting machine which is operable in timed relationship with an adjacent punching or stamping machine or other material working machine, so as to cut the scrap material therefrom into portions of suitable length for easy disposal.

Another object is to provide a scrap cutter operated from the reciprocable ram of a punch press to cut the scrap material into portions of predetermined length.

Another object is to provide a scrap cutter, as set forth in the preceding objects, wherein a lost-motion connection is provided between the scrap cutter and the machine to which it is connected so that only such portion of the motion of the machine is transmitted to the scrap cutter as is necessary for the operation thereof.

Another object is to provide a scrap cutter, as set forth in the preceding objects, wherein the cutting plunger thereof is operably connected to the reciprocable ram of a punch press through an adjustable lost-motion connection which may be varied according to the thickness of the material being cut.

Other objects and advantages of the invention will become apparent during the course of the following description of the accompanying drawings, wherein:

Figure 1 is a fragmentary front elevation of a punch press having a material-feeding device and scrap cutter associated therewith and operable thereby in accordance with the present invention;

Figure 2 is a vertical section along the line 2—2 in Figure 1, showing the scrap cutter of the present invention in front elevation and with the operating bracket of the punch press shown in dotted lines;

Figure 3 is a central vertical section through the scrap cutter of Figure 2, taken along the line 3—3 in Figure 4;

Figure 4 is a rear end elevation of the scrap cutter shown in Figure 2; and

Figure 5 is a top plan view thereof.

Referring to the drawings in detail, Figure 1 shows a scrap cutter, generally designated 10, according to a preferred form of the invention, as connected to a conventional punch press, generally designated 11, the latter of which operates a material feeding device, generally designated 12. The details of the punch press 11 are conventional and form no part of the present invention, and the material feeding device 12 is disclosed and claimed in my co-pending application, Serial No.

2

576,821, filed February 8, 1945, which issued as U. S. Patent No. 2,428,493 on October 7, 1947, for Stock feeding mechanism for punching, stamping, and cutting machines.

For purposes of the present disclosure, it is sufficient to state that the punch press 11 has a vertically movable plunger 13 reciprocable in guide members 14 attached to the upper portion of the punch press frame (not shown). Secured to the lower end of the plunger 13 is a ram 15 having a punch unit 16 secured to the lower end thereof. The punch unit 16 is also conventional and may be of any suitable type, depending upon the nature of the workpieces to be punched or stamped. For purposes of illustration, the punch unit 16 is shown as consisting of a base or support 17 to which a pair of spaced punches 18 and 19 are connected. The punches 18 and 19 cooperate with die portions (not shown) in a conventional die unit 20. The latter is secured to the bed 21 of the punch press 11 by any suitable means, as by the bolts 22. The die unit 20 is provided with material guides 23 and 24 located on opposite sides thereof and configured to guide a strip of material 25 over the die unit 20 so as to be properly positioned for subjection to the punching or stamping operations of the punch unit 16.

The material 25 is preferably in the form of a 30 relatively thin elongated strip or band, such as strip sheet material, and is fed to the punch unit 16 and die unit 20 by means of the material feeding device 12. The feeding mechanism of the feeding device 12 is operated step-by-step in response to the reciprocating motion of the press plunger 13 by means of a bracket 26 secured thereto as at 27 and having a downwardly extending arm 28 operably connecting the plunger 13 to the material feeding device 12. At its opposite 35 end the bracket 26 has a second downwardly extending arm 29 having a slotted or recessed portion 30 through which an operating connection is made to the cutting machine 10 in order to operate the latter in response to the operation of the plunger 13 in a manner analogous to the operation of the material feeding device 12.

The cutting machine 10 consists of a base or bed 31 (Figures 2 and 4) having spaced vertical bores 32 in which are received the lower ends of 40 uprights or strain rods 33. The base 31 also is provided with oppositely extending bosses 34 forming supporting feet and having slots 35 therein (Figure 5) for the reception of bolts or other suitable fasteners 36 by which the cutting machine 10 is secured to the bed 21 of the punch

press 11 (Figure 1). The uprights 33 are preferably in the form of shafts serving for the guiding and retaining of a vertically reciprocable platen 37 having vertical bores 38 near the opposite ends thereof for receiving the uprights 33. Secured as at 39 to the platen 37 intermediate the uprights 33 (Figure 4) is a downwardly extending cutting blade 40 having an approximately V-shaped cutting edge 41 thereon, the cutting blade 40 being mounted in a recess 42 and the fasteners 39 being threaded through holes 43 into threaded bores 44 in the platen 37 (Figure 3).

The bed 31 is provided with a similar recess 45 and threaded bores 46 for the reception of an lower cutting blade 47 with a cutting edge 48 arranged in shearing relationship with the cutting blade 40 and secured in the recess 45 by fasteners 49 passing through holes 50 in the cutting blade 47 and threaded into the bores 46. The fasteners 49 also pass through holes 51 in a vertically extending and laterally bent material guide 52 having an elongated horizontal slot 53 aligned with the cutting edge 48 and adapted to slidably receive the material strip 25 (Figure 3).

The upper part of the platen 37 is provided with upwardly projecting spaced ribs or ears 54 having aligned bores 55 (Figure 3) in which is mounted a pivot pin 56. The latter also passes through a bore 57 in the projecting arm 58 of an eccentric member 59 and has its opposite faces closely adjacent the inner faces of the ribs or ears 54. The upper portion of the eccentric arm 59 is provided with a bore 60 which receives and is engaged by an approximately cylindrical eccentric 61 mounted upon or forming a portion of a shaft 62 (Figures 3 and 4). The shaft 62 is journaled at one end in a bore 63 passing horizontally through a top member 64 having vertical bores 65 receiving the reduced diameter portion 66 of the uprights 33, thereby providing annular shoulders 67 thereon as seats for the top member 64. The upper ends of the uprights 33 are threaded as at 68 to receive nuts 69 (Figure 4) by which the top member 64 is retained in position upon the uprights 33.

The opposite end of the shaft 62 is journaled in a bore 70 in a face plate 71 which is secured by the fasteners 72 to the top member 64, the fasteners 72 passing through holes 73 in the face plate 71 and threaded into threaded holes 74 in the top member 64 (Figure 3). The top member 64 is provided with a cavity 75 having an inner abutment wall 76 parallel to the inner wall 77 of the face plate 71. The abutment surfaces 76 and 77 are spaced apart at approximately the same separation as the thicknesses of the eccentric 61 and eccentric arm 59 (Figure 3).

The top member 64 is provided with a horizontally extending boss 78 having an end face 79 against which the rear surface 80 of a stop support 81 is in contact. The stop support 81 is provided with a hub 82 having an internal bore 83 receiving the eccentric shaft 62 and having a squared bore 84 adapted to receive the correspondingly squared end 85 of the eccentric shaft 62 (Figure 3). These parts are held in assembly by an end plate 86 secured to the end of the shaft 62 by a bolt 87, threaded into a hole 88 therein by way of a hole 89 in the end plate 86. The stop support 81 is provided with bosses 90 having threaded bores 91 therein arranged with their axes at an angle to one another (Figure 2) and having stop screws 92 threaded therethrough and secured in position by lock nuts 93. The stop screws 93 are provided with rounded ends 94 for

engagement with the opposite sides 95 of an operating arm 96. The latter is provided with a hub 97 having a bore 98 (Figure 3) journaled on the outer surface 99 of the hub 82. Thus, the operating arm 96 is loosely and swingably mounted upon the hub 82 and applies its operating force to the shaft 62 by way of the stop screws 92, thereby forming a lost-motion connection therebetween.

Extending laterally from the opposite sides 95 of the operating arm 96 are parallel ribs 100 forming with the face 101 of the arm 96 a guide groove 102 for the reception of a rectangular block 103 slidable therein during adjustment. The arm 96 is provided with spaced holes 104 for the reception of a stud 105 (Figure 2) passing through one of the holes 104. The stud 105 is integral with the block 103 and carries a roller 107 having a bore 108 therefor. The outer ends 109 and 110 of the stud 105 are of reduced diameter and threaded to receive nuts 111 and 112 respectively, these engaging washes 113 and 114 so as to hold the parts in assembly and permit free rotation of the roller 107 upon the stud 105. The roller 107 engages the slot or recess 30 in the arm 29 of the bracket 26, a sliding connection being thus established therebetween.

Operation of the invention

Prior to the operation of the scrap cutting machine 10 of this invention, the stop screws 92 are adjusted in the bosses 90 (Figure 2) of the stop support 80 until the swinging of the operating arm 96 in response to the reciprocation of the press plunger 13, bracket 26 and bracket arm 29 provides a sufficient amount of lost motion to impart a suitable length of stroke to the platen 37 to move the cutting blade 40 a sufficient distance toward and away from the cutting blade 47 to accommodate the thickness of the material 25 being worked upon.

When these adjustments have been made and the material 25 has been threaded through the material feeding device 12 and the guides 23 and 24 of the die unit 20, the punch press 11 is started in operation. As the press plunger 13 moves downward, the punch unit 16 stamps out work pieces from the material strip 25, and on its return stroke, the plunger 27 operates the feeding device 12 to advance the material strip 25 step by step in the direction of the scrap cutter 10 through its connection with the plunger 13, by the bracket 26.

When the material strip 25 reaches the scrap cutter 10, the operator threads it through the elongated aperture 53 in the material guide 52 so that it is guided into the space between the cutting edges 41 and 48 of the cutting blades 40 and 47 (Figure 3). As the arm 29 of the bracket 26 reciprocates in response to the reciprocation of the press plunger 13, it engages and swings the operating arm 96 (Figure 2) by reason of the engagement of the roller 107 in the slot 30. The swinging of the operating arm 96 causes it to engage the rounded end 94 of the stop screws 92, imparting this swinging motion to the stop support 81.

The swinging of the stop support 81 rotates the eccentric shaft 62 and eccentric 61 through its connection therewith by way of the squared bore 84 and squared shaft portion 85. The rotation of the eccentric 61 in the bore 60 of the eccentric arm 59 causes the latter to move downwardly (Figure 4), thereby moving the platen 37 and cut-

ter blade 41 downwardly into shearing engagement with the cutting blade 47 and material strip 25 therebetween by reason of the pivotal connection between the eccentric arm 59 and pivot pin 56. This action cuts off the end portion of the material strip 25 into pieces of any desired length, depending upon the feeding rate of the material feeding device 12. After the cutting action has been performed, the cutting blade 40 and platen 37 move upward in response to the upward motion of the operating arm 96, bracket arm 29, bracket 26 and press plunger 13. The foregoing cycle of operations is repeated indefinitely as long as the material strip 25 is fed into the scrap cutter 10 by the material feeding device 12.

While I have shown and described my invention in detail, it is to be understood that the same is to be limited only by the appended claims, for many changes may be made without departing from the spirit and scope of my invention.

What I claim is:

1. A scrap cutter for connection to and operation by a material-working machine having a reciprocable member, said cutter comprising a frame having a guide structure, a blade carrier movably engaging said guide structure for guidance thereby, a cutting blade connected to said frame, a cutting blade connected to said blade carrier in shearing relationship with said frame blade, and mechanism interconnecting said carrier and said machine member and responsive to the reciprocation thereof for moving said carrier in timed relationship therewith, said mechanism including a lost-motion connection disposed between said machine member and said carrier whereby to move said carrier a predetermined distance in response to a different distance of motion of said machine member.

2. A scrap cutter for connection to and operation by a material-working machine having a reciprocable member, said cutter comprising a frame having a guide structure, a blade carrier movably engaging said guide structure, for guidance thereby, a cutting blade connected to said frame, a cutting blade connected to said blade carrier in shearing relationship with said frame blade, and mechanism interconnecting said carrier and said machine member and responsive to the reciprocation thereof for moving said carrier in timed relationship therewith, said mechanism including a lost-motion connection disposed between said machine member and said carrier whereby to move said carrier a predetermined distance in response to a different distance of motion of said machine member, and having an adjusting device adjustably engaging a portion of said lost-motion connection.

3. A scrap cutter for connection to and operation by a material-working machine having a reciprocable member, said cutter comprising a frame having a guide structure, a blade carrier movably engaging said guide structure for guidance thereby, a cutting blade connected to said frame, a material guide disposed adjacent said frame blade for guiding material to said frame blade, a cutting blade connected to said blade carrier in shearing relationship with said frame blade, and mechanism interconnecting said carrier and said machine member and responsive to the reciprocation thereof for moving said carrier in timed relationship therewith, said mechanism including a lost-motion connection disposed between said machine member and said carrier whereby to move said carrier a predetermined dis-

tance in response to a different distance of motion of said machine member.

4. A scrap cutter for connection to and operation by a material-working machine having a reciprocable member, said cutter comprising a frame having a guide structure, a blade carrier movably engaging said guide structure for guidance thereby, a cutting blade connected to said frame, a material guide disposed adjacent said frame blade for guiding material to said frame blade, a cutting blade connected to said blade carrier in shearing relationship with said frame blade, and mechanism interconnecting said carrier and said machine member and responsive to the reciprocation thereof for moving said carrier in timed relationship therewith, said mechanism including a lost-motion connection disposed between said machine member and said carrier whereby to move said carrier a predetermined distance in response to a different distance of motion of said machine member, and having an adjusting device adjustably engaging a portion of said lost-motion connection.

5. A scrap cutter for connection to and operation by a material-working machine having a reciprocable member, said cutter comprising a frame having a guide structure, a blade carrier movably engaging said guide structure for guidance thereby, a cutting blade connected to said frame, a cutting blade connected to said blade carrier in shearing relationship with said frame blade, a rotary element mounted on said frame, an eccentric device connected to said rotary element, a motion-transmitting element operatively interconnecting said eccentric device and said blade carrier, and motion-converting mechanism operatively connecting said rotary element and said machine member and responsive to the reciprocation thereof for rotating said rotary element.

6. A scrap cutter for connection to and operation by a material-working machine having a reciprocable member, said cutter comprising a frame having a guide structure, a blade carrier movably engaging said guide structure for guidance thereby, a cutting blade connected to said frame, a cutting blade connected to said blade carrier in shearing relationship with said frame blade, a rotary element mounted on said frame, an eccentric device connected to said rotary element, a motion-transmitting element operatively interconnecting said eccentric device and said blade carrier, and motion-converting mechanism operatively connecting said rotary element and said machine member and responsive to the reciprocation thereof for rotating said rotary element, said motion-converting mechanism including a lost-motion connection disposed between said machine member and said rotary element whereby to move said carrier a predetermined distance in response to a different distance of motion of said machine member.

7. A scrap cutter for connection to and operation by a material-working machine having a reciprocable member, said cutter comprising a frame having a guide structure, a blade carrier movably engaging said guide structure for guidance thereby, a cutting blade connected to said frame, a cutting blade connected to said blade carrier in shearing relationship with said frame blade, a rotary element mounted on said frame, an eccentric device connected to said rotary element, a motion-transmitting element operatively interconnecting said eccentric device and said blade carrier, and motion-converting mechanism

operatively connecting said rotary element and said machine member and responsive to the reciprocation thereof for rotating said rotary element, said motion-converting mechanism including a lost-motion connection disposed between said machine member and said rotary element, said lost-motion connection including an adjusting device adjustably engaging a portion of said lost-motion connection whereby to move said carrier a predetermined distance in response to a different distance of motion of said machine member.

8. A scrap cutter for connection to and operation by a material-working machine having a reciprocable member, said cutter comprising a frame having a guide structure, a blade carrier movably engaging said guide structure for guidance thereby, a cutting blade connected to said frame, a cutting blade connected to said blade carrier in shearing relationship with said frame blade, a rotary element mounted on said frame, an eccentric device connected to said rotary element, a motion-transmitting element operatively interconnecting said eccentric device and said blade carrier, and motion-converting mechanism operatively connecting said rotary element and said machine member and responsive to the reciprocation thereof for rotating said rotary element, said motion-converting mechanism including an arm freely swingable about the axis of said rotary element, spaced stops operatively connected to said rotary element and selectively engageable with said arm in response to the swinging thereof, and an operation connection disposed between said arm and said machine member.

9. A scrap cutter for connection to and operation by a material-working machine having a reciprocable member, said cutter comprising a frame having a guide structure, a blade carrier movably engaging said guide structure for guidance thereby, a cutting blade connected to said frame, a cutting blade connected to said blade carrier in shearing relationship with said frame blade, a rotary element mounted on said frame, an eccentric device connected to said rotary element, a motion-transmitting element operatively interconnecting said eccentric device and said blade carrier, and motion-converting mechanism operatively connecting said rotary element and said machine member and responsive to the re-

ciprocation thereof for rotating said rotary element, said motion-converting mechanism including an arm freely swingable about the axis of said rotary element, spaced stops operatively connected to said rotary element and selectively engageable with said arm in response to the swinging thereof, and an operation connection disposed between said arm and said machine member, at least one of said stops being adjustably movable relatively to said rotary element for varying the point of engagement thereof with said arm.

10. A scrap cutter for connection to and operation by a material-working machine having a reciprocable member, said cutter comprising a frame having a guide structure, a blade carrier movably engaging said guide structure for guidance thereby, a cutting blade connected to said frame, a cutting blade connected to said blade carrier in shearing relationship with said frame blade, a rotary element mounted on said frame, an eccentric device connected to said rotary element, a motion-transmitting element operatively interconnecting said eccentric device and said blade carrier, and motion-converting mechanism operatively connecting said rotary element and said machine member and responsive to the reciprocation thereof for rotating said rotary element, said motion-converting mechanism including an arm freely swingable about the axis of said rotary element, spaced stops operatively connected to said rotary element and selectively engageable with said arm in response to the swinging thereof, and an operation connection disposed between said arm and said machine member, said operating connection including a projection on said arm and an elongated actuating portion connected to said machine member and slidably engaging said projection.

JOHN HALLER.
